TIME RECORDER MECHANISM

Elmer G. Streckfuss, Cincinnati, Ohio, assignor to
The Cincinnati Time Recorder Company, Cincinnati, Ohio, a corporation of Ohio

Application November 20, 1935, Serial No. 50,682

10 Claims. (Cl. 234—43)

My invention relates to time recorders, and more particularly to the provision of a time recorder with an operating lever located at the front of the machine, which may be rocked to the right or the left in order to make a recording. In commercial establishments it is usual to find a number of aisles through which the workmen pass in entering and leaving the shop. These aisles are usually defined by racks which carry the time cards of the employes. In the morning an employe passes a rack, takes his card out and makes a recording, and then places his card in a rack at the other side of the recorder. In leaving the shop, the reverse procedure is followed, so that the cards are again placed in the original racks. In an arrangement of this sort, there is usually a congestion of employes passing the recorder at starting time in the morning, at noon, and at night at quitting time. I have conceived that if a recorder could be provided with a front handle which was adapted to rock as above described, and if the recorder could be so designed that the employe could rock the operating handle in the direction of his own travel, and the recorder would indicate, according to the direction in which the handle was actuated, whether the recording was "in" or "out", a material saving in time could be attained.

It is, therefore, an object of my invention to provide a time recorder in which the operating lever is at the front of the machine, and in which recordings are made by rocking the handle either to the right or to the left.

It is another object of my invention to provide a time recorder as above outlined, in which the rocking of the operating handle to one side will shift the card tray to one side, and the rocking of the handle in the other direction will shift the card tray to the other side.

It is a further object of my invention to provide such a time recorder in which, no matter on which side of the path of the employes it may be located, a movement of the handle in the direction of travel of the employe when entering the shop will make an "in" recording, and in which a movement of the handle in the direction of travel of the employe when leaving the shop will make an "out" recording.

These and other objects of my invention which will be set forth hereinafter or will be apparent to one skilled in the art upon reading these specifications, I accomplish by that certain construction and arrangement of parts of which I shall now describe a preferred embodiment. Reference is now

made to the drawings which form a part hereof, and in which:

Figure 1 is a front view of my invention, parts of the recorder frame and handle being broken away for greater clarity.

Fig. 2 is an elevation of a part of the device as seen from the left in Fig. 1.

Fig. 3 is a sectional view along the line 3—3 of Fig. 1.

Fig. 4 is a detail perspective view of the rocker cam member.

Fig. 5 is a view of an exemplary form of card which may be used in my device.

Briefly, in the practice of my invention, I provide a time recorder of somewhat conventional construction, having a card tray 1, which is provided with integral lugs 2 by which the tray is mounted upon the shaft 3, and other hook-shaped lugs 4, which rest upon the shaft 5, whereby the tray is firmly mounted for sliding movement along the shafts 3 and 5. The sliding movement of the tray is limited by the collars 6 on the shaft 3.

Centrally located at the front of the recorder is a split boss 7, which provides bearings for the handle shaft 8; a collar 9 provided with a set screw is fixed on the shaft between the arms of the boss 7, and serves to fix the longitudinal position of the shaft 8. A handle 10 is provided in order to rock the shaft 8, and may be fastened thereto by any well known means. The inner end of the shaft 8 carries an arm 11, the upper end of which is provided with a cam roller 12 mounted upon a screw stud 12a. The lower end of this arm 11 is adapted to swing between the adjusting screws 13a mounted in lugs 13, which are formed integrally with the recorder base or frame. These adjusting screws serve as stop members to limit the degree of swing of the operating handle 10. The collars 6 are preferably adjusted to become operative somewhat in advance of the screws 13a.

The connection between the card tray and the operating handle is as follows: Pivoted upon a standard 14, which is also integral with the frame of the recorder, by means of the stud 14a, is the lever 15, the upper end of which is connected to one of the lugs 2 on the card tray by the link 16; mounted on the lower end of the lever 15 is a bracket 17; passing through a hole in the bracket 17 and attached to the upper end of the arm 11, is a rod 18; upon the rod 18 on either side of the bracket 17 are the small compression springs 19, the outer ends of which abut against collars 20. By these means, referring to Fig. 1, as the operating handle is rocked to the right, the rod 18 moves to the right, carrying with it the collars 55.

20, which, bearing against the bracket 17 through the springs 19, urge the lever 15 in a counter-clockwise direction, and the card tray is shifted to the left. Likewise, when the operating handle is moved to the left, the card tray is shifted to the right. The collars 20 are of course adjusted on the rod 18, so that when the handle 10 is in a neutral position, the card tray 1 is likewise in a neutral position. The direction of shift of the card tray upon movement in a given direction of the operating handle may be reversed by simply moving the bracket 17 from the position shown in Fig. 1, to a point equally removed on the other side of the pivot 14a and mounting it at 17a. By these means a time recorder of this type may be placed on each side of an aisle through which workmen pass. In this situation, although both recorder handles will be rocked in the direction of movement of the workmen, one will in effect be rocked clockwise and the other counter-clockwise. It is only necessary, therefore, to place the bracket 17 at the position 17a in one of the recorders, and then identical cards may be used in both, with an "in" column on the left, and an "out" column on the right, for example.

In order to transmit rocking motion from the shaft 8 to the cross shaft 21 for operating other elements of the recorder, which is disposed at 30 right angles thereto, I mount on the shaft 21 a collar 22, which carries a cam plate 23. The cam plate 23 is provided with a shallow notched cam surface 23a, which is clearly shown in Fig. 4. The collar 22 is so mounted upon the shaft 21, 35 that when the operating handle 10 is in a neutral position, the cam roller 12 rests in the center of the notch 23a. Now when the operating handle is rocked either to the right or the left, the shaft 21 is rocked in a clockwise direction as seen in 40 Fig. 3.

Fixed upon the end of the shaft 21, as seen in Fig. 2, is a bell crank lever 24, having arms 24a and 24b. A spring 25, connected to the frame and to the end of the arm 24a, urges the shaft 45 21 in a counter-clockwise direction, so as to return the mechanism to a neutral position. Connected to the arm 24a is a rod 26, which actuates certain other parts of the recorder, as is well known in the art, such as a ribbon shifting mechanism, and a time wheel centering mechanism, 50 none of which form a part of my invention, and which I shall therefore not describe. At the extreme end of the arm 24b, a linkage indicated generally at 27 serves to actuate the ribbon feed, 55 as is also well known in the art. The hammer shaft is indicated at 5, and is actuated as follows: Pivoted intermediate the length of the arm 24b is a link 29, having a projecting lug 29a, and an overhanging trigger 29b, which rests upon a lug 60 28a, mounted on the shaft 5; the member 29 is urged in a counter-clockwise direction by a small spring 28b; integral with the bell-crank 24 is a boss 24c, in which is mounted an adjustable stop screw 24d. Now when the shaft 21 is rocked as 65 above described, the member 29 tends to pull downwardly on the member 28a, rocking the shaft 5 in a clockwise direction. Upon further rocking of the shaft 21, however, the lug 29a will abut the stop screw 24d, whereby the member 29 70 will be forced toward the right, until it finally slips off the lug 28a, whereupon the shaft 5, under the influence of the spring 30, which is fastened to an arm 31 and to the frame, will snap back to its original position. The hammer 32 will thereby be caused to strike and make a record

75 on a card. It is understood that the card tray 1 is provided with mechanism indicated generally at 34 and well known in the art, whereby an abutment 33, upon which the bottom of a card rests, is intermittently or continuously shifted, whereby over-printing is eliminated.

An exemplary form of card is shown in Fig. 5. It will be noted that the card is divided longitudinally into a right hand and a left hand column, one of these being designated "in", and the other "out". In my exemplary embodiment, the abutment 33 shifts upwardly twice a day, so that each transverse line represents one-half of a day. The first record made will be "in", at the top of the card, and the second will be "out", 15 also on the same line. The mechanism may be adjusted as above described, so that the "in" column may be either the right or left hand column, although probably the most natural arrangement will be that indicated in Fig. 5. During the noon hour, the recorder having been properly adjusted, the abutment 33 will shift upward one notch, so that the afternoon "in" and "out" recordings will appear in the next line below. With an arrangement providing for fourteen shifts upwardly of the abutment 33, one card will suffice for a week. At the end of the week the abutment 33 will return to the bottom, as is well known in the art.

It is to be understood that, except as mentioned in the claims which follow, the type of recorder to which my invention is applied forms no limitation thereon, and that different forms of my preferred embodiment may be made without departing from the spirit of my invention.

Having thus fully described my invention, what I claim as new and desire to secure by Letters Patent, is:—

1. In a time recorder, a laterally shiftable card tray and an operating handle movable toward the right or toward the left of the recorder, mechanism connecting said operating handle with said card tray, whereby as the handle is moved in one direction the card tray is shifted to one side, and as the handle is moved in the other direction the card tray is shifted to the other side, and mechanism connecting the operating handle with the printing mechanism of the recorder, whereby said movement of said operating handle actuates said printing mechanism.

2. In a time recorder having a printing mechanism, a laterally shiftable card tray and an operating handle for the recorder movable toward the right or toward the left of the recorder, the combination of a mechanical linkage including a spring connecting said operating handle with said tray, whereby as the handle is moved in one direction the card tray is shifted to one side, and as the handle is moved in the other direction the card tray is shifted to the other side, and means for actuating said printing mechanism by both of said movements, stops to limit the shifting of the tray, stops to limit the movement of the operating handle, said tray limiting stops being positioned to become operative before the handle limiting stops.

3. In a time recorder having a printing mechanism, a laterally shiftable card tray and an operating handle adapted to be moved toward the right or toward the left of the recorder; mechanism including a lever connecting said operating handle with said card tray, whereby as the handle is moved in one direction the card tray is shifted to one side, and as the handle is moved in the other direction the card tray is shifted to the other side.

other side, and mechanism connecting the operating handle with the printing mechanism of the recorder for actuation thereof by said movement, the former mechanism being changeable, 5 by a change in the class of said lever, to alter the direction in which the card tray is shifted upon movement of the operating handle in a given direction, for the purpose described.

4. In a time recorder having a laterally shift-
10 able card tray, an operating handle for the re-
corder movable toward the right or toward the
left of the recorder, and a main rocking lever; a
connection between one end of said rocking lever
and said tray, and a resilient connection between
15 the other end of said rocking lever and said op-
erating handle, whereby movement of said op-
erating handle may be continued after completion
of the tray shifting movement.

5. In a time recorder having a laterally shift-
20 able card tray, an operating handle for the re-
corder movable toward the right or toward the
left of the recorder, and a main rocking lever; a
connection between one end of said rocking lever
and said tray, a resilient connection between
25 the other end of said rocking lever and said op-
erating handle, said resilient connection comprising
a bracket provided with a hole on said rock-
ing lever, a rod connected to the operating handle
and passing through said hole, and springs sur-
30 rounding said rod on either side of said bracket
and maintained in contact therewith by collars on
said rod.

6. In a time recorder, a main operating shaft
for the recorder, a card tray shiftable for in and
35 out registrations, an operating handle movable in
opposite directions from a neutral position, con-
nections therefrom to actuate the operating shaft
in the same direction irrespective of the direction
of movement of said handle, connections from
40 said handle, including a lever, to shift the card
tray to in or out position, depending upon which
direction the handle is moved, and means for
changing the class of said lever to alter the di-
rection of shift of the tray with relation to di-
45 rections of movement of the handle.

7. In a time recorder having a printing mecha-
nism and a frontal operating handle which is

movable to the right or to the left of the recorder, a main transverse shaft operatively connected to said printing mechanism, and mechanism for translating the rocking motion of said handle in one direction into a rocking motion of said shaft 5 in a given direction, and means for translating the rocking motion of said handle in the other direction into a rocking motion of said shaft in said given direction.

8. In a time recorder having a printing mecha-
nism and a frontal operating handle which is
movable to the right or to the left of the recorder, a main transverse shaft operatively connected to
10 said printing mechanism, mechanism for trans-
lating the rocking motion of said handle into a
15 rocking motion of said shaft, said mechanism
comprising a cam rider actuated by said handle,
and in operative relation with a notched cam
surface fixed on said shaft.

9. In a time recorder having a printing mecha-
nism, a frontal operating handle adapted to rock
a shaft extending into the recorder substantially
perpendicularly to the front thereof, and a main
transverse shaft for actuating the printing mech-
anism in the recorder, and means for transmit-
20 ting the rocking of said operating handle shaft
to said transverse shaft, whereby the latter is
rocked in the same direction regardless of the
direction of rocking of the operating handle shaft.

10. In a time recorder having a printing mech-
anism and a frontal operating handle adapted to
rock a shaft extending into the recorder substan-
tially perpendicularly to the front thereof, and a main
transverse shaft for actuating the print-
35 ing mechanism in the recorder; means for trans-
mitting the rocking motion of said operating
handle shaft to said transverse shaft, whereby the
latter is rocked in the same direction regardless
of the direction of rocking of the operating han-
40 dle shaft, said transmitting means comprising a
member fixed on said transverse shaft and carry-
ing a cam plate having a shallow V-shaped cam
surface, and a member on said operating handle
shaft carrying a cam rider adapted in a neutral
45 position of the respective parts to rest in the
apex of the V-shaped cam surface.

ELMER G. STRECKFUSS.
